UNITED STATES PATENT OFFICE.

ROBERT E. MCEDLOWNEY, OF NEW MARTINSVILLE, WEST VIRGINIA, ASSIGNOR TO
NEW MARTINSVILLE GLASS MFG. CO., OF NEW MARTINSVILLE, WEST VIRGINIA,
A CORPORATION OF WEST VIRGINIA.

DESIGN FOR A CANDLESTICK HOLDER OR SIMILAR ARTICLE.

Application filed January 2, 1929. Serial No. 29,481. Term of patent 3½ years.

To all whom it may concern:

Be it known that I, ROBERT E. MCEDLOWNEY, a citizen of the United States, residing at New Martinsville, in the county of Wetzel and State of West Virginia, have invented a new, original, and ornamental Design for a Candlestick Holder or Similar Article, of which the following is a specification, reference being had to the accompanying drawing, forming part thereof.

Figure 1 is a perspective view of a candle-

stick holder or similar article, showing my new design.

Figure 2 is a top or plan view of a candlestick holder or similar article, showing my new design.

Figure 3 is a front view thereof.

I claim:

The ornamental design for a candlestick holder or similar article, as shown.

ROBERT E. MCEDLOWNEY.
